[57] **CLAIM**

The ornamental design for a tooling to form pairs of three-sided pouches, as shown and described.

DESCRIPTION

FIG. 1 is a front perspective view of a first embodiment of tooling to form pairs of three-sided pouches, illustrating tooling to form two side-by-side pouches;

FIG. 2 is a top plan view of FIG. 1;

FIG. 3 is a front elevational view of FIG. 1;

FIG. 4 is a right end view of FIG. 1; the other end being a mirror image thereof;

FIG. 5 is a bottom plan view of FIG. 1;

FIG. 6 is a rear elevational view of FIG. 1;

FIG. 7 is a front perspective view of a second embodiment of tooling to form pairs of three-sided pouches, illustrating tooling to form four side-by-side pouches;

FIG. 8 is a front perspective view of a third embodiment of tooling to form pairs of three-sided pouches, illustrating tooling to form 12 side-by-side pouches;

FIG. 9 is a front perspective view of a fourth embodiment of tooling to form pairs of three-sided pouches, illustrating tooling to form eight side-by-side pouches;

FIG. 10 is a top plan view of a further embodiment of the tooling shown in FIG. 1, having a modified exit opening; and,

FIG. 11 is a bottom plan view of FIG. 10.
